Philip Farrell's Composition for making
Candles
Secttor's Patent

The Schedule referred to in these Secttor's Patent and making part of the
same containing a description in the words of the said Philip Farrell him-
self of his improvement being a discovery in the composition and mode of
making candles

Be it known that I Philip Farrell of the City, County and State of New York have
made an improvement in the useful art of being a discovery in the composition
of mode of making candles which is described as following Take 100 lbs of melted
tallow prepared in the usual way, Take 12 or 15 lbs of white pine turpentine,
boil it ⁱⁿ water about 24 hours for evaporating its oil or spirits, add the tallow and
turpentine thus prepared with which make candles by dipping or casting in the
usual way.

With this composition good cheap candles can be made much cheaper
than in the common mode, the saving being in the difference of the price of tallow
and turpentine used. The tallow casting ^{about} a 10 cent candle the turpentine about one
cent per lb. to be proper both together. The discovery here claimed and desired to
be secured by Secttor's Patent consists in using a quantity of boiled white pine tur-
pentine, with melted tallow, instead of tallow alone in making candles, being
a great saving in the expense
